INVENTOR.

William E. Small.

BY

J. B. McGinn.

ATTORNEY.

UNITED STATES PATENT OFFICE.

WILLIAM E. SMALL, OF BROOKLYN, NEW YORK.

REINFORCED SHANK.

Application filed September 22, 1925. Serial No. 57,808.

My invention relates to improvements in shoes, and particularly to those of the turn or welt variety wherein a leather shank or insole is further stiffened by the addition of a metallic strip.

My invention has for its object the reenforcing of ladies' and men's shoes of a particular designed last, and causes the shoe to conform throughout the various steps in 10 its manufacture with the identical lines of the last without change or modification.

Another object of the invention is to produce a reenforced shank or insole that in no way reduces the foot room in the shoe, 15 but at the same time reenforces the same to the extent of having therein an arch support. The reenforcing plate or member holds the shape of the shoe at all times yet allows the necessary elasticity.

20 The further object of my invention is to provide a shank stiffener so constructed, that it will be no thicker than the material of the shank itself when applied and pressed into position, and at the same time be so constructed and arranged that its upper and lower holding faces, while conforming to the various curves of the last, will hold the shoe from spreading.

My invention further consists in certain 30 new and novel details of construction that will add materially to each shoe by retaining its original lines, and make the shank or insole a combination of strength and durability as well as utility. The arrangement as illustrated, permits of a particular style of shoe being constructed or built without any of its original lines being lost by adding here and there as is usual in building shoes. These and other objects and features 35 of the invention will be hereinafter described and pointed out particularly in the appended claims.

The invention as at present preferred will be more clearly understood by reference to the drawing which illustrates merely examples of means for putting my invention into practice, and wherein:—

Fig. 1 is a plan view of my leather shank or insole showing my improvement applied;

50 Fig. 2 is a longitudinal section on lines 2—2 of Fig. 1 showing my stiffener in position therein;

Fig. 3 is a cross section taken on lines 3—3

of Fig. 1, the same being on an enlarged scale so as to show how the stiffener clamps 55 the edge of the slot and thereby prevents spreading;

Fig. 4 is a detail perspective of the stiffener member before it is cut the desired length;

Figs. 5 and 6 show inverted views of various modifications of the stiffener member.

In the building of shoes for men and women, more particularly the latter whose shoes have the high heels, it has become a serious question to keep the shank of the shoe from breaking down, and thereby lose the shape of the last that the shoe was designed to carry. Any shank or insole, either 65 with or without a suitable stiffener therein, that does not remain firm, is liable to injure the foot of the wearer. Again, to get these shanks stiff enough to hold not only the shoe in shape, but to hold the foot of the 70 wearer firm therein, has been the aim of the trade. It has been found that by the addition of one or more strengthening strips of various kinds, made to the shank, that they contributed to the losing of the original 75 lines intended to be produced by the particular last without gaining the desired object.

The body portion 10 of the shank is made 80 from leather-board or any other suitable material, which, after being cut the desired shape will be skived about its edges so that when it is applied to the shoe, it will fit properly when placed in position, conforming to the interior thereof without any protruding edges to mar the contour of the inner lines. A narrow slot 11 is cut through the leather shank for a suitable distance, and into this slot is applied my improved 85 pressed metallic stiffener 12.

The stiffener above referred to comprises a strip of sheet metal bent upon itself providing a wide upper face 13 and having the two ends meeting centrally so as to form a vertical web 14, which in turn is passed through the slot 11, then the ends 15 and 16 are folded over and pressed firmly on the opposite side of the leather shank. Inasmuch as the slot in the leather shank is only 90 long enough to allow my stiffener to be 105 applied, it will be seen that there is no possi-

bility for the said stiffener member 12 to creep or become dislodged in any way whatsoever.

My reenforced shank forms a new and improved method of applying strength so that the original lines of any design last may be built into a shoe, and yet retain the exact lines to the completion of the shoe; secondly, with the stiffener so applied it gives the shank that elasticity necessary in the shoe, particularly for women. Again, with my reenforced shank applied to a shoe, it acts as an arch support to the foot.

After the stiffener member 12 has been applied to the shank, the arms or wings 15 and 16 are turned over and the same are pressed to the thickness of the material of the shank as shown at 17, thereby imbedding the upper and lower arms of the stiffener member in the body of the leather shank, as shown at 18 and 19. It is at this time the body portion of the shank, and its reenforced member 12, receive their particular curve 20 to conform to the particular last. The leather shank and its stiffener member, when properly pressed, as above noted, are only the thickness of the leather shank at its thickest part, and the process of imbedding the upper and lower arms or wings of the stiffener in the leather of the shank prevents the latter from any tendency to spread.

It will be noted my improved stiffener is applied to the shank and held in proper relation thereto without the use of any other agency, it remaining in its proper position with respect to the shank, and at the same time holding its longitudinal curve to correspond to that of the lines of the last.

In Fig. 5 is shown a modification wherein is illustrated the stiffener detached and turned upside down for the purpose of bringing out more clearly the construction and arrangement of its under side. Instead of the arms as shown in Figs. 1, 2, 3 and 4, in this style it is preferred to provide the central web 14 with spaced projections 21 and 22, each extending in opposite directions to each other from the bottom of the web 14. It may be found advantageous to turn these projections or fingers 21 and 22 after the stiffener has been applied in the slot 11, or they may be turned over at the time the pressure is applied to press said stiffener to the thickness of the body portion of the shank.

The construction illustrated in Fig. 6 is similar to that described in Fig. 5. In this modification the stiffener is formed of tubing compressed to form the reenforcing member and web, and the web 14 is provided with retaining arms which are cut from the web itself. When the stiffener is applied in the slot 11, the retaining arms 27 are turned outwardly and pressed into the material of the shank, which will hold the stiffener secure

as in the other designs. These retaining members 27 may be opposite each other or staggered, and may be opened partially before being inserted, so that when applied to the shank, the retainers may be spread out preparatory to being pressed. The upper and lower faces of the reenforcing member after being pressed are parallel to each other.

As has been noted, ladies' shoes have reenforced shanks or half soles which usually extend from the ball of the foot to the breast of the heel. This is the case in all welt shoes, but when the shoe is to be a turned shoe, then it is usual to use a leather reenforced shank from the ball of the foot to the heel. In welt shoes a whole insole is provided, and the reenforced member 12 is applied in the same way as has been explained, so as to get the same results.

In accordance with the provisions of the patent statutes I have herein described the principal form of my invention which I now consider to represent the best embodiment thereof, but I desire to have it understood that the various forms of stiffeners are only illustrative and that the invention can be carried out in other ways than those shown and described, but all are intended to come within the scope of the claims. Also, while the design of the stiffeners are shown in various forms, they may be changed or altered to meet the particular requirement without interfering in any way with the general results which the locking or fastening means was designed to accomplish.

What I claim as new is:

1. The combination of a shank having a slot therein, and a metallic reenforcing member fitting within said slot and having on each side outspreading arms extending over the top and bottom of the shank, and lying flush with the upper and lower surfaces of the shank.

2. Means for stiffening and retaining the shape of shoe shanks, comprising a body adapted to be disposed through the material of the shank, and provided with retaining members on its edges adjacent the upper and lower surfaces of the shank, said retaining members being pressed into the material of the shank to lie flush with said surfaces.

3. An article of manufacture for use in reinforcing shoe shanks comprising an elongated strip of metal, portions of said strip to either side of and spaced from a line longitudinally bisecting the strip being bent inwardly toward each other to lie flush with the remaining portion of the strip, and then bent outwardly with their opposed faces meeting to form a web, and then each of said portions being bent outwardly from each other substantially at right angles to the web to form retaining members.

4. The method of stiffening shoe shanks, consisting in slitting the shank between the

ends thereof and through the portion to be stiffened, inserting in the slit a sheet metal member of about the same length as the slit, bending the portions of the metal member above and below the shank down upon the shank to engage the material of the shank above, below and about the slit, and then

pressing said bent portions into the material of the shank to lie flush with the upper and lower surfaces thereof, and in the same 10 operation pressing said shank and stiffener to conform to the final shape of the shank.

In testimony whereof I affix my signature.

WILLIAM E. SMALL.
